BERNHARD MEISSNER, OF WOODSIDE, NEW YORK

INTERNAL COMBUSTION MOTOR

Application filed November 7, 1929. Serial No. 405,342.

My invention relates to internal combustion motors; more particularly to two-cycle motors, which have long been considered as most efficient from a strictly mechanical point of view, although they are universally known to be less efficient in respect to the utilization of the full calorific heat value of the fuel to be burned therein. However, the principles of this invention are also applicable to four-cycle engines.

The objects I have pursued in the development of my invention have generally been those which guide the automotive engineer, when he attempts to perfect the internal combustion engine in the many modifications in which it is used today.

Some of the outstanding objects of my improvements are:

First, to incorporate in the design of a reciprocating internal combustion engine elements which, as far as possible, contribute a turbine character to such an engine.

Second, to apply the turbine principle to a reciprocating internal combustion motor by providing one or more points at which a substantially continuous combustion of fuels takes place, the mechanical energy created by said combustion being transmitted to the point at which it is to be applied by the means of reciprocating engine gearing.

Third, to provide a motor in which the combustion chambers of a reciprocating two-cycle internal combustion motor are connected, at the beginning of the power stroke, in continuous rotation to one or more common ignition points.

Fourth, to provide an engine which requires extrinsic ignition when started, but no such ignition being required during the continuous performance of the engine, because a continuing explosion takes place at one or more fixed points in my engine during normal operation.

Fifth, to provide one or more sets of valve gearing each comprising a combustion or ignition, an intake and an exhaust valve, which connect in periodical rotation with a multiplicity of combustion chambers.

Sixth, to provide a reciprocating internal combustion engine in which power is trans-

mitted from a multiplicity of combustion chambers which are located substantially in one plane to a substantially centrally disposed crank shaft.

Seventh, to derive a rotative momentum from a substantially circularly arranged, rotatable multiple combustion unit by gearing the pistons of said unit to a yoke which is rotatable on a stationary eccentric crank head.

Eighth, to provide in a motor of this kind substantially stationary valve gears which slidably connect a revolving combustion chamber unit.

Ninth, to provide upon an internal combustion engine means allowing the gas-type slidable adjustment of valve gears upon a rotating cylinder head.

Tenth, to sub-divide in a motor of this kind the exhaust valve for the purpose of using the pressure of the exhaust gas which is first exhausted for expediting the removal of the rest of the exhaust gas from and for washing out the combustion chamber.

Eleventh, to provide independent suction means for bringing about the injection of an efficient fuel mixture into the combustion chambers.

Further objects of my invention will be more clearly elucidated by the following description of my invention and will be emphasized in the annexed claims. I illustrate one modification of design involving the principles of my invention in the accompanying drawings, in which,

Figure 1 is a partly sectioned side elevation of my internal combustion motor.

Figure 2 is a corresponding partly sectioned rear view (taken from the right side of Figure 1) the section being carried through on one half of the motor partly along the plane in which one set of combustion chambers is radially arranged, partly, on the outside thereof through the center of the valve gears and substantially through the center of the housing.

Figure 3 shows, in a parallel perspective view, a section of the eccentric head, the eccentric yoke and some of the piston rods connecting thereto.

Figure 4 shows, in a parallel perspective view, a section of the valve ring, sectioned through the combustion valve.

Figure 5 shows a developed view of the cross section of the combustion chamber and the exhaust valve abutting thereupon, said section being taken along a cylindrical plane through the center of the exhaust means.

Similar numerals refer to similar parts throughout the various views.

The motor housing 11 is, in the drawings, exemplarily provided with a base 12. In a practical application the method, in which the housing is mounted, depends largely on the use for which the motor is intended. Whereas a heavier base, but of the type of base 12 indicated, may be used with my invention as a stationary source of motive power, a large variety of methods of mounting suggest themselves in the application in automotive vehicles, vessels and aircraft; the adaptation of my invention for the latter uses may involve extensive modifications of the design of the housing.

The housing essentially consists of a bottom half 13, and a cover 14 and cap 15, closing the top of the housing. The shaft 16 is rotatably supported in the housing by ball bearings 17 and 18 on the left and right (rear and front) end of the motor respectively (Figure 1). Next to ball bearing 17, in a bearing 19, on the inside of the housing, is mounted shank 21 of the eccentric head 20, the inside of which is substantially concentric to the shaft 16 and allows its free rotation, whereas the eccentric yoke 22 is rotatably mounted, by means of the rollers 23 retained in cage 24, upon the eccentric outer circumference of the eccentric head 20. The eccentric yoke 22 is thrustwise retained on the eccentric head 20 by the retaining flanges 25 and 37.

Upon the circumference of the eccentric yoke are provided, next to each other, two annular grooves 26 and 27, in which are swingably suspended the two sets of piston rods 28 and 29, respectively.

One piston rod 30 which belongs to the right set of piston rods 29 is solidly mounted upon the eccentric yoke 22, whereas all the other piston rods 28 and 29 are mounted upon pivots 31 and 32, respectively, which bridge the grooves 26 and 27. Pivots 31 and 32 are endwise retained in the solid rim 33 between the grooves 26 and 27, by a split wire ring 34 which keeps the groove 35 in the rim 33 in alignment with the groove 36 in the pivots 31 and 32.

The cylinder head 40 is essentially concentric to the shaft 16 and is solidly mounted upon said shaft in its hub 41. The cylinder head consists of a flange 42 extending outwardly from said hub 41 and of a chamber body 43 which laterally extends from said flange 42 over the eccentric head 20 and which is substantially annular and concentric to

the shaft 16. In this chamber body 43 are arranged two parallel rows of respectively staggered cylinder openings 44 and 45, which are radially disposed in respect to the main shaft 16. In these cylinder openings are slidably arranged the pistons 46 with piston rings 47. The pistons are hinged upon the ends of the piston rods 28, 29 and 30 by means of pins 48.

In the drawings the cylinder openings 44 and 45 are shown bored through the whole thickness of the head body 43 and the cylinder openings are substantially closed on their outer ends by a sleeve 49 shrunk around the head body or otherwise substantially integrally united thereto. Two rims 50 are provided on the cylindrical surface of sleeve 49 and confront a groove in which are arranged the slides 51, the ends of which overlap each other at 52 in piston ring fashion so that, combined, they represent a valve ring, which slidably extends around the whole sleeve 49. To substantially the extent in which the respective rows overlap each other, the cylinder openings 44 and 45 break through the sleeve 49 in the shape of segmental openings 54 and 55, which are substantially in peripheral alignment with each other below the ring made up of slides 51. The closing action of the ring made up of slides 51, in respect to the segmental openings 54 and 55 is improved upon by stuffing rings 56 made up of several sections, which overlap each other at their ends in piston ring fashion and which are retained in grooves of sleeve 49 by pins 61. The slides 51 or those of these slides which are particularly exposed to high heats are provided with cooling chambers 57 which are enclosed between halves of said slides integrally joined at seams 53. The chambers 57 are bridged by inserts 58 at those points where the head body is to be approached from the outside through the ring made up by the slides 51. The cooling chambers 57 are provided with cooling water and said water is drained therefrom through pipes 59, which enter upon said chambers from the sides, and the other ends of which extend through suitable openings 60 in the cover 14. Other pipes 62 enter upon the slides 51 in similar fashion and serve to introduce lubricating oil between the stuffing rings 56 and the slides 51, said oil being introduced into the respective grooves in the slides through the opening 63.

The outside cylindrical shell 64 of the motor, which is formed by parts of the bottom half 13 and the cover 14, is substantially cylindrically disposed in respect to the shaft 16. Said shell 64 carries on its inside lugs 65 which are shown in the drawings to be held in said shell by screws 66. The inner faces of lugs 65 represent a cylindrical surface 67 which is slightly eccentric in respect to the heretofore enumerated concentric

parts of the motor, such as the shaft, the cylinder head, the slides 51, the parts of the housing and the shell 64. Between the eccentric faces 65 and the slides 51 slidably fit 5 four annular segments 68, peripheral movement of which will cause them to wedge more or less between the faces 67 and the slides 51, on account of the eccentrically disposed outer and inner faces of said annular segments. Alongside of their eccentric outer faces these annular segments carry spur gear sections 69 which are concentrically disposed in respect to shaft 16 and which are curved 10 to mesh into the worms 70; these worms are 15 rotatably lodged in suitable pockets 71 of the shell 64 upon shafts 72. The worms 70 are thrustwise retained in the pockets 71 and their shafts 72 are provided with hexagon heads 73 at their ends, which permit the 20 rotation of the worms for the purpose of the following adjustment: Assuming the point of the shortest distance of the eccentric face 67 from the shaft 16 to be near the lower right hand corner of Figure 2, approximate- 25 ly at a point 74, an adjustment of the two annular segments, which are arranged upon the circumference of the ring made up of the slides 51 to the left of point 72, and of the other two annular segments 68 to the right 30 and above said point, towards said point by means of rotation of the adjusting worms 70, will cause the inner concentric face of said annular segments to close upon the slides 51 which are also sidewise retained in said 35 annular segments by the centrally extending flanges of said annular segments 68. I thus provide an accurate adjustment, allowing the slides 51 to be held onto the sleeve 49 with adequate pressure to provide a practically 40 gastight fit between said parts; this fit is accentuated by the stuffing rings 56, without creating an excessive friction between said parts, which would cause the creation of undue heat and which therefore would im- 45 pair the efficiency of my motor. Between adjoining annular segments I allow clearance spaces 76 of such width as to allow a close adjustment of the sliding fit between the slides 51 and the sleeve 49 during sub- 50 stantially the whole period of life of my motor.

Pipes, which are slidably arranged in the shell 64, approach the valve ring made up of the slides 51, radially, from the outside of 55 the motor, serve to adduce to the openings 54 and 55 in the sleeve 49 gas, air and an igniting spark, when these openings are in alignment with the respective pipes, and serve to retain the slides 51 peripherally, so that they 60 are substantially stationary in respect to the housing of the motor. Since the annular segments 68 are peripherally adjusted, slots 62 are substantially stationary in respect to the housing of the motor. Since the annular segments 68 are peripherally adjusted, slots 65

referred to are an air pipe 78, gas injector pipes 79 and a pipe 80 in which the spark plug 81 is mounted and through which a conductor is insulatedly carried into the ignition chamber 82; that chamber is formed 70 by a cavity on the inside of the respective slide 51. The end 83 of said conductor is disposed on the inside of said chamber 82 so as to allow a spark to jump from the end thereof to the extension on the grounded 75 pipe 80. The pipe 80 is retained in the slide by a pipe thread on its outside which fits into a threaded hole in the insert 58 bridging the cooling chamber 57 of slide 51. The pipes 78 and 80 are mounted in corresponding 80 fashion in the respective slides 51, the pipes 78 opening into a cavity in the bottom slide 51 which is similar to cavity 82, whereas the injector pipes 79 open almost directly onto the cylindrical face of the sleeve 49. 85

All cylinders or combustion chambers 44 and 45 are surrounded by cooling chambers and by water jackets 84 and 85, respectively, which are supplied with cooling water and from which said water is drained by channels 86 and 87, located in the flange 42 of the cylinder head or in ribs 88 reenforcing said flange, and respectively connecting to two holes 89 and 90, in the shaft 16. These holes 89 and 90 approach the terminals of channels 86 and 87 from the two ends of the motor, and where the hole 89 issues from said shaft at its front end, said shaft is rotatably coupled to a stationary water pipe 91 by water-tight coupling 92. On the outside of the 100 motor, in the rear thereof, the hole 90 issues through holes radially penetrating the wall of said shaft into a centrifugal water pump 93 with a water connection 94 which serves to bring about the circulation of the water 105 and which is also suitably coupled to supply water to the cooling chambers 57 of the slides 51 making up the valve rings, by means of the pipes 59.

The pump 93 is mounted on a suitable extension 95 on the rear of the bottom half 13 of the housing and similar means (not shown) may be provided in order to pump oil for the lubrication of the valve ring through the pipes 62, and to supply oil to the 110 stationary eccentric head 20, through a pipe connection 96; from said connection oil is distributed to the surface of said eccentric head by means of a multitude of channels 97, which are appropriately arranged to issue 115 radially from said eccentric head, providing lubrication for the eccentric yoke, said oil being from there distributed to the piston rods and pistons owing to the centrifugal action of the rotating cylinder head parts. 120

Along a circular center line an exhaust manifold 99 approaches the chamber body 43. A developed section of the chamber body and of the manifold along said line is shown in Figure 5. The manifold 99 is held against 130

4
a circular rim 100 which protrudes from the side of the chamber body 43, by the tension of the springs 101 extending around the exhaust pipes 102, 103 and 104, which are slidably mounted in the bottom half 13 of the housing; said springs 101 are held in compression between the inner wall of the housing and the exhaust manifold 99. A suitable gasket 105 serves to prevent the gases 10 in the manifold from dissipating into the inside of the housing. The exhaust pipes 102, 103 and 104 are connected to separate chambers 106, 107 and 108 of the manifold, said chambers being separated from each other by intermediary walls and by cross pieces 109 of the gasket 105.

It will be noticed in Figure 2 that the cylinders 46, when they have reached their extreme position of movement out of the cylinder openings 44 and 45, (the cylinder heads at the lower end of the chamber body 43), will clear openings 110 by which the chamber body is perforated along the line 98. These openings 110 in the walls of the combustion chambers 44 and 45 open, directly and indirectly, respectively, through the rim into the exhaust manifold 99. The openings 110 in the cylinders 45 open intermediately upon a passageway 111, which extends through the chamber body between the cylinder holes 44. The chambers 111 issue upon the manifold 99 through holes 112 in the chamber body, corresponding in location and size to the openings 110, which issue directly from cylinder openings 44 into the manifold.

For the interval, during which the pistons 46 clear the openings 110, said openings, or the corresponding openings 112 in the case of the combustion chambers 45, face the exhaust manifold 99. The first exhaust gases escape into the chamber 108 and are carried from that chamber through the exhaust pipe 104 by means of an ejector nozzle 113 into the exhaust pipe 103 into which the exhaust gases pass through the chamber 107 when the respective combustion chambers are at their lowest position. The exhaust gases issuing into the chamber 107 at a pressure lower than that, at which they escape into the chamber 108, the gases in exhaust pipe 103 will be sucked out of said pipe 103 by the gases issuing into said exhaust pipe through the ejector 113 from chamber 108. From the exhaust pipe 113 the exhaust gases pass through a suitable muffler out into the air. The exhaust pipe 102 which is connected to the chamber 106 and which is connected to the combustion chamber after the exhaust gases have escaped therefrom into the chambers 108 and 107, connects to an exhaust pump 114 mounted upon the motor shaft, between the front end of the housing and the coupling 92. The exhaust gas passing 60 through this pump is also issued into the air.

My engine functions as follows:

According to the quality of the fuel to be used in my motor, and also according to the efficiency of the exhaust means used in connection with my invention at a specific speed, the fuel mixture is injected by pressure or sucked in by said exhaust means from carburetors through one or more injector nozzles 70 75 79, which issue, through the valve ring 51 upon the sleeve 49, and it enters upon the combustion chambers 44 and 45 through those of the segmental openings 54 and 55 which are temporarily in alignment with said nozzles during the clockwise rotation (Figure 2) 80 of the chamber body 43 of the cylinder head 40. During further clockwise rotation of the cylinder head the pistons 46 in the combustion chambers which chambers have thus been filled with the gas mixture move outwardly in said chambers and compress the mixture, said outward movement of the pistons being brought about by the riding of the eccentric yoke 22 onto the most eccentric part of the eccentric head 20, said eccentric yoke being operatively connected to the pistons in the chambers under consideration, by the connecting rods 28 and 29. The eccentric yoke reaches the point of greatest distance from the shaft 16 in the arrangement shown in the drawings at the highest point thereof so that the gas in the combustion chambers under consideration is compressed to a pressure suitable for an efficient explosion, when the respective segmental openings 54 and 55 slide below the ignition chamber 82 in the valve ring at the 90 95 100 top of the motor. Some of the gas mixture contained in the combustion chambers 44 and 45 above the piston 46 escapes into the explosion chamber 82 and is there ignited by a substantially continuous spark passing from the end 83 of the electrical conductor in the pipe 80 to said pipe, said spark having as a source of power a primary or secondary high tension generator as commonly used with an internal combustion engine.

By a substantially continuous spark I have reference in the above to an uninterrupted rotation of electrical discharges as distinguished from the exactly timed electric discharge in a four-cycle combustion motor. Of course the electric discharges may be timed in such a manner that there is a spark each time one of the combustion chambers comes into alignment with the spark plug. But ordinarily this is not necessary. In fact, the electric spark, or the functions of the spark plug may be dispensed with altogether after the engine has been started, the ignition of the compressed gas in the combustion chambers, as they consecutively approach the ignition chamber 82, taking place as soon as the burning gases in the ignition chamber come into touch with the gas mixture in the approaching combustion chambers. In the manner of some Diesel-type and semi-Diesel-type en- 110 115 120 125 130

gines I may of course also provide a hot point in the explosion chamber which is brought up to heat from the outside, before the motor is started and which retains this heat once the 5 engine is running, because it is exposed to the continuous explosion of the gas mixture, which is ignited at this point. However, as long as the engine functions normally, no extrinsic ignition means are required, and to the 10 skilled designer a great number of automatic and semi-automatic contrivances suggest themselves which bring about an electric discharge or which furnish other ignition means at those times when the engine does not function 15 properly or when it is started up. A governor for instance may be provided for on my motor which automatically closes the high tension circuit when the engine is standing still or turning slowly at a speed lower than 20 that which is required to bring about the so-called continuous explosion.

It is common practice in internal combustion motor design to provide means by which the spark is advanced, or retarded, either at 25 the option of the operator of the engine or automatically, as a direct function of the speed at which the motor is travelling, and in some instances of the load. In my design I show the ignition to take place at the point 30 of highest compression, when the combustion chamber is at the top of the motor, by means of the electric spark. When the engine has come up to a speed at which there is a continuous explosion, the gas mixture in the 35 combustion chambers approaching the spark plug will be ignited by the hot gases in the explosion chamber before the respective combustion chambers attain the status of highest compression, because the ignition 40 chamber extends to the left from the spark plug and the burning gases therein will ignite the gas mixture in the combustion chamber as soon as the combustion chamber connects with the ignition chamber. Thus 45 I provide, automatically for an earlier ignition when the motor is at speed than at the time the engine is started up.

The relation of the location of the ignition chamber in respect to the status of compression in the approaching combustion chambers may however be additionally controlled and regulated by varying the position of the eccenter head 20. The drawings show that the eccenter head 20 is clamped by the bearing cap 19; it may be rotated, to the extent of a slight clockwise or counterclockwise angular displacement, by a corresponding rotation of the shank 21 of the eccenter head 20 in its bearing 19 in the housing. As an 50 additional refinement of the control of the angular displacement of the eccenter head in relation to the valve ring, gearing may be introduced which brings about such angular displacement of the shank 21 in the bearing 55 automatically, as a function of the speed of

the motor, in the same manner in which governors now serve to control the advancement or the retardation of the spark in an automobile engine.

A continuous explosion taking place in the valve ring, that ring is exposed to very high heats and I therefore have provided a cooling chamber inside of the valve ring, alongside of the ignition chamber 82. Great care must also be taken to prevent the pressure 70 of explosion to be dissipated along the faces of the valve ring 51 and of the sleeve 49, which slide upon each other. The stuffing rings 56, which are preferably made of a fire 75 proof material, serve to prevent lateral dissipation of the force of the explosion from out of the explosion chamber, and the careful and accurate adjustment of the valve ring upon the sleeve which is brought about by the annular segments 68 and by the means, 80 which cause these segments to wedge more or less tightly between the housing and the valve ring, according to the settings of the operator, prevents undue propagation of the 85 explosion peripherally along the contacting surfaces of the sleeve 49 and the valve ring.

The gas mixture having been ignited at the top position of the combustion chambers, the pressure of the exploded and exploding gas forces the piston downward in the combustion chambers. The pistons move downward in the combustion chambers as the cylinder head continues its clockwise rotation; and the pressure of the exploded gas, pushing the pistons in the direction of said movement 90 downward in the combustion chambers and being transmitted to the eccenter yoke by the piston rods, causes the said yoke to slide clockwise around the eccenter head, carrying 95 along the cylinder head and the shaft 16, 100 since the eccenter yoke and the cylinder head are positively coupled to each other by means of the connecting rod 30 which solidly connects, at one end, to the eccenter yoke, the 105 hinged suspension of its other end in a piston in one of the combustion chambers allowing play for angular displacement of the connecting rod 30 from the center line of the 110 respective combustion chamber which is necessary on account of the respective eccentricity of the centers around which the yoke and the cylinder head rotate substantially coextensively.

When, after further clockwise rotation of the cylinder head, the force of explosion has 115 been substantially spent, and the pistons are pushed for such a distance out of the combustion chambers, that they clear the openings 120 110 which open from said combustion chambers towards the circular rim 100, the respective openings 110 have reached a position of alignment with the chamber 108 of the exhaust manifold and the burned gases are forced from the combustion chamber into 125 said exhaust chamber 108 and from there, 130

through the nozzle 113 into the pipe 103. In the pipe 103 a suction of the gases contained therein, away from the exhaust chamber 107, is caused by the gases issuing from nozzle 113, so that the exhaust gases are sucked from the combustion chambers ahead of the combustion chamber under consideration and at the same time air is sucked into the combustion chambers, which connect to exhaust chamber 107, through the pipe 78, said air taking partly or wholly the space of the exhaust gases remaining in the combustion chamber connecting to exhaust chamber 107. The connection between the combustion chamber and the pipe 78 is however interrupted, as the cylinder head proceeds in its clockwise rotation, and the suction applied to the combustion chamber from the exhaust chamber 107 decreases the pressure of the air contained in the combustion chamber, the pressure of said air being further reduced when positive vacuum is applied to the combustion chamber through the exhaust chamber 106 from pump 114, as soon as the combustion chamber comes into alignment with that exhaust chamber. In the drawings the pipe 78, which supplies air for flushing purposes during the exhaust operation, is shown to issue upon the open air. To accentuate the flushing action of the air entering upon the combustion chamber which is in alignment with pipes 78, said air may be supplied under pressure, said pipe being connected to a blower or compressor which is also driven by the motor and which may be aligned upon one end of the shaft, next one of the pumps at one or the other end. The suction of the pump 114 evacuates the combustion chamber to such an extent that suction is applied from the combustion chamber, which we are observing, to the first one of the injector pipes 79, which said combustion chamber aligns with upon further clockwise rotation of the cylinder head. This suction is however interrupted as soon as the gas mixture has been partly sucked into the combustion chamber and would issue therefrom into the exhaust, if the combustion chamber would remain connected to the exhaust. The connection between the combustion chamber and the vacuum is however interrupted when the piston in the respective combustion chamber continues to move upwardly again, after having passed the lower part of the vertical center line of the motor from right to left (Figure 2) during the clockwise rotation of the cylinder head. At a point substantially corresponding to the point at which the pistons cleared the exhaust openings 110 to the right of the center line, said openings 110 are covered up by the piston at a corresponding position on the combustion chamber to the left of said center line. Thus the openings 110 are completely closed towards the vacuum when the second injector pipe 79 comes into alignment with

the combustion chamber, the gas mixture from said second injector pipe filling the evacuated combustion chamber, either owing to the low pressure in said combustion chamber or owing to the pressure under which the gas is carried to the motor from the carburetor through the second injector pipe 79.

We thus have completed one complete rotation of the cylinder head, describing the functions of the motor, the piston in the combustion chamber under consideration having substantially performed two cycles or the respective overlapping parts of two cycles.

I claim:

1. In an internal combustion engine, a housing, a cylinder head rotatably mounted in said housing, valve means radially slidably arranged in said housing and slidably abutting upon said cylinder head, combustion chambers arranged in said cylinder head and opening upon said valve means, and pistons reciprocatably disposed in said combustion chambers and operatively reactionably connected with said housing.

2. In an internal combustion engine, a housing, a cylinder head rotatably mounted in said housing, valve means radially slidably arranged in said housing and slidably abutting upon said cylinder head, combustion chambers substantially radially arranged in said cylinder head and opening upon said valve means, and pistons reciprocatably disposed in said combustion chambers and operatively reactionably connected with said housing.

3. In an internal combustion engine, a housing, a cylinder head rotatably mounted in said housing, valve means radially slidably arranged in said housing and slidably abutting upon said cylinder head, combustion chambers arranged in said cylinder head and opening upon said valve means, pistons reciprocatably disposed in said combustion chambers and operatively reactionably connected with said housing, and adjustable segments, wedge-like disposed between said housing and said valve means.

4. In an internal combustion engine, a housing, a cylinder head rotatably mounted in said housing, valve means substantially stationarily arranged in said housing and slidably abutting upon said cylinder head, combustion chambers arranged in said cylinder head and opening upon said valve means, an eccentric mounted in said housing, pistons reciprocatably disposed in said combustion chambers and operatively reactionably connected with said eccentric, and eccentric peripherally adjustable annular segments, wedge-like disposed between said housing and said valve means.

5. In an internal combustion engine, a housing, a cylinder head rotatably mounted in said housing, valve and ignition means radially slidably arranged in said housing

- and slidably abutting upon said cylinder head, combustion chambers substantially radially arranged in said cylinder head and opening upon said valve means, and pistons reciprocatably disposed in said combustion chambers operatively reactionably connected with said housing.
6. In an internal combustion engine, a housing, a cylinder head rotatably mounted in said housing, valve and ignition means radially slidably arranged in said housing, and slidably abutting upon said cylinder head, combustion chambers substantially radially arranged in said cylinder head and opening upon said valve means, an eccenter mounted in said housing, pistons reciprocatably disposed in said combustion chambers, piston rods hinged upon said pistons, and a yoke slidably rotatable upon said eccenter, operatively hinged upon some of said piston rods and solidly connected with one of said piston rods so as to rotate in substantially equal angular displacement therewith.
7. In an internal combustion engine, a housing, a cylinder head rotatably mounted in said housing, valve and ignition means peripherally substantially stationarily arranged in said housing and adjustable towards and slideable upon the cylindrical circumference of said head, combustion chambers substantially radially arranged in said cylinder head and opening upon said valve means, and pistons reciprocably disposed in said combustion chambers and operatively reactionably connected with said housing.
8. In an internal combustion engine, a housing, a cylinder head rotatably mounted in said housing, annular segments with valve and ignition chambers supported in said housing and slideable upon the cylindrical circumference of said head, two sets of combustion chambers substantially radially arranged in said cylinder head in substantially parallel planes and alignedly and alternately opening upon said segments from opposite sides, and pistons reciprocably disposed in said combustion chambers and operatively reactionably connected with said housing.
9. In an internal combustion engine, a housing, a cylinder head rotatably mounted in said housing, valve and ignition means substantially annularly arranged in said housing and slideable upon the cylindrical circumference of said head, and two sets of combustion chambers substantially radially arranged in said cylinder head in substantially parallel planes, said combustion chambers of said two sets being respectively offset in zig-zag arrangement and the overlapping parts of said combustion chambers of said two sets opening upon said valve and ignition means.
10. In an internal combustion engine, a housing, a cylinder head rotatably mounted in said housing, valve means substantially
- stationarily arranged in said housing to slide onto a side of said head, an exhaust manifold arranged to slide in said housing into abutment with a face of said cylinder head, combustion chambers substantially radially arranged in said cylinder head and opening upon said valve means and upon said exhaust manifold, pistons reciprocatably disposed in said combustion chambers and adapted to close said combustion chambers towards said exhaust manifold, and means operatively and reactionably connecting said pistons with said housing.
11. In an internal combustion engine, a housing, a cylinder head rotatably mounted in said housing, valve means radially slidably arranged in said housing and slideable upon the cylindrical circumference of said head, an exhaust manifold coaxially slidably retained in said housing and slideably abutting upon the side of said cylinder head, combustion chambers substantially radially arranged in said cylinder head and opening radially upon said valve means and laterally upon said exhaust manifold, and pistons reciprocatably disposed in said combustion chambers and adapted to close said combustion chambers towards said exhaust manifold.
12. In an internal combustion engine, a housing, a cylinder head rotatably mounted in said housing, valve means substantially stationarily arranged in said housing and slideable upon said housing, an exhaust manifold substantially stationarily retained in said housing and slideably abutting upon said cylinder head, combustion chambers substantially radially arranged in said cylinder head and opening upon said valve means and upon said exhaust manifold, and pistons reciprocatably disposed in said combustion chambers and adapted to close said combustion chambers towards said exhaust manifold, said exhaust manifold consisting of separate compartments adapted to connect in rotation to each of said combustion chambers in said revolving cylinder head.
13. In an internal combustion engine, a housing, a cylinder head rotatably mounted in said housing, valve means substantially stationarily arranged in said housing and slideable upon said housing, an exhaust manifold substantially stationarily retained in said housing and slideably abutting upon said cylinder head, combustion chambers substantially radially arranged in said cylinder head and opening upon said valve means and upon said exhaust manifold, pistons reciprocatably disposed in said combustion chambers and adapted to close said combustion chambers towards said exhaust manifold, eccentric means mounted in said housing and operatively and reactionably connected with said pistons, said exhaust manifold consisting of

- separate compartments adapted to connect in rotation to said combustion chambers in said revolving cylinder head, the compressed exhaust gas entering from said combustion chamber upon some of said compartments due to its expansion, and suction means connected to the remainder of said compartments and evacuating the combustion chambers opening thereupon.
14. In an internal combustion engine, a housing, a cylinder head rotatably mounted in said housing, valve means slidably arranged in said housing and slidable upon said housing, an exhaust manifold slidably retained in said housing and slidably abutting upon said cylinder head, combustion chambers substantially radially arranged in said cylinder head and radially opening upon said valve means and laterally upon said exhaust manifold, pistons reciprocatably disposed in said combustion chambers and adapted to close said combustion chambers towards said exhaust manifold, eccentric means mounted in said housing and operatively and reactionably connected with said pistons, and means for supplying air for flushing purposes through said valve means to said combustion chambers, when said combustion chambers are not closed toward said exhaust manifold, so that the air passes from one end of said chambers substantially to the other end thereof, and then laterally out through said manifold.
15. In an internal combustion engine, a housing, an annular cylinder head rotatably mounted in said housing, combustion chambers substantially radially arranged in said cylinder head, pistons reciprocatably disposed in said combustion chambers, and a stationary eccentric extending from said housing into said head and operatively and reactionably connected with said pistons.
16. In an internal combustion engine, a housing, an annular cylinder head rotatably mounted in said housing, combustion chambers substantially radially arranged in said cylinder head, pistons reciprocatably disposed in said combustion chambers, stationary means extending from said housing into said head, and piston rods centrally attached to said pistons and eccentrically hinged upon said means substantially in alignment with said chambers.
17. In an internal combustion engine, in combination with a rotatable annular cylinder head, combustion chambers substantially extending from the outer surface of said head to the inside thereof, opening upon the inside of said cylinder head, and segmentally closed at their outer ends by the surface of said head.
18. In an internal combustion engine, in combination with a rotatable annular cylinder head, annular valve and ignition means slidably accommodated in circular tracks upon the outer surface of said head, combustion chambers substantially extending from the outer surface of said head to the inside thereof, and partly closed at their outer ends by the surface of said head; and the openings at the outer ends of said chambers being in circular alignment with each other and issuing upon said means.
19. In an internal combustion engine, in combination with a rotatable annular cylinder head, annular valve and ignition means, slidably accommodated in circular tracks upon the outer surface of said head, combustion chambers substantially extending from the outer surface of said head to the inside thereof, and partly closed at their outer ends by the surface of said head; adjoining ones of said chambers overlapping each other peripherally as well as in the direction of the axis of said head, and the openings at the outer ends of said chambers being in circular alignment with each other and issuing upon said means.
20. In an internal combustion engine, in combination with a rotatable annular cylinder head, annular valve and ignition means, slidably accommodated in circular tracks upon the outer surface of said head, combustion chambers substantially extending from the outer surface of said head to the inside thereof, and partly closed at their outer ends by the surface of said head, and an ignition chamber in said means, exceeding in length the peripheral distance along the outer circumference of said head between adjoining combustion chambers.
21. In an internal combustion engine, in combination with a rotatable annular cylinder head, annular valve and ignition means, slidably accommodated in circular tracks upon the outer surface of said head, combustion chambers substantially extending from the outer surface of said head to the inside thereof, and partly closed at their outer ends by the surface of said head, and an ignition chamber in said means, exceeding in length the peripheral distance along the outer circumference of said head between adjoining combustion chambers, and of such width that the openings in said head at the outer ends of said combustion chambers fully issue upon said ignition chamber.
22. In an internal combustion engine, in combination with a rotatable annular cylinder head in a stationary housing, combustion chambers substantially extending from the outer surface of said head to the inside thereof, a segmental exhaust manifold slidably resting upon and tensioned in said housing against the sides of said head in alignment with the pitch circle of openings laterally issuing from said chambers through the side of said head, and reciprocating pistons in said

chambers operatively connected with said housing and clearing said openings of the respective chambers, when said chambers slide past said manifold during the rotation of said head.

Signed at New York in the county of New York and State of New York this 19th day of October A. D. 1929.

BERNHARD MEISSNER.
